UNITED STATES PATENT OFFICE.

GUST O. MORTON, OF ROCKFORD, ILLINOIS.

LENGTH-DETERMINING DEVICE FOR DRYING FORMS.

Application filed August 16, 1919. Serial No. 318,065.

To all whom it may concern:

Be it known that I, GUST O. MORTON, a citizen of the United States, residing at Rockford, in the county of Winnebago and State of Illinois, have invented certain new and useful Improvements in Length-Determining Devices for Drying Forms, of which the following is a specification.

This invention relates in general to apparel apparatus, and has more particular reference to the holding of knitted articles on drying forms, as for example, the holding of hosiery or mittens on forms during the drying process.

16 In the course of preparing knitted articles, such as stockings and mittens for the market, it is necessary to dry them on appropriate forms. The knitted article in a moist condition is drawn onto the shaping form, which is either heated internally or passed through a drying compartment. In large knitting factories the drying rooms are of considerable size and each attendant takes care of a large number of forms, that 20 is, places the stockings or other knitted articles on and removes them from the forms. Since articles originally of a common size are very frequently drawn onto the forms to unequal lengths, due to the haste of the attendant and also to the lack of proper gages for determining the length, the articles do not dry to uniform lengths. Consequently they must be later matched or paired which takes up considerable extra time. But perhaps the greatest cause of unequal lengths 35 is the shrinking and drawing of the article onto the form during the drying process.

It is the purpose of the present invention to provide a simple and practical means for 40 insuring drying of stockings, socks, mittens and other similar knitted articles to uniform lengths and to permit the attainment of this object without imposing such attention and care on the part of the operator as would delay his work in handling a given number of drying forms.

In furtherance of this general object, I have aimed to provide in co-operative relation with each drying form a pair of spring 50 pressed members adapted to yieldingly engage the opposite sides of the article near the bottom thereof to so hold the article in connection with the form as to prevent shrinking, drawing or shortening in any manner during the drying process. These gripping or article engaging members are

arranged in a novel manner to effectually perform the desired function and permit of quick actuation to and from their operative and inoperative positions. I have also 60 aimed to provide a simple means for actuating the presser members for simultaneously returning a plurality of them to inoperative position to permit quick removal of the articles from the forms.

65 Other objects and attendant advantages will be appreciated as the invention becomes better understood by reference to the following description when considered in connection with the accompanying drawings, in which—

Figure 1 is a front elevation of a drying and shaping form equipped with an article-gripping means embodying my improvements;

75 Fig. 2, an end view, partly in section, of my improvements; and

Fig. 3, a plan sectional view taken on the line 3—3 of Fig. 1.

80 My improvements are designed for use in connection with drying and shaping forms of the kind employed in knitting factories for drying knitted articles of various descriptions. The forms are made to suit the particular size, shape and configuration of 85 the articles to be dried, it being obvious that so far as the present invention is concerned, it is immaterial whether the form be for a stocking, sock, mitten or any other similar article of a kind that is open at one end and 90 adapted to be drawn onto a form for drying and shaping. In the present exemplification of my improvements, a form such as illustrated and claimed in my United States Letters Patent No. 1,323,642, Dec. 2, 1919, 95 is shown. It consists of a hollow body having curved opposite walls 4 joined by a coupling 5 which constitutes a shaping and guiding edge. The heating medium is delivered to the form through the base 6 thereof, and the upper portion 7 is shaped to receive the knitted article.

100 In practice, the stocking, mitten or other article is drawn onto the form in a moistened condition, and so far as I am aware, 105 in all equipment heretofore employed or provided for drying rooms, there have been no simple and practical means provided for insuring against uneven shrinking and drawing of the articles while on the forms.

110 My invention contemplates equipping each form with a simple device for engaging

the lowermost portion of an article for holding it to the proper length and against drawing or shrinking during the drying process. It further contemplates a gripping means of this character adapted to be quickly and easily operated so as not to take up the attendant's time or decrease the work capacity of a drying room.

With the foregoing in mind I have provided a pair of gripping members 8 and 9 each having one or more serrated gripping edges 11 shaped to conform to the periphery of the drying form and engage opposite sides of the article evenly at spaced points throughout substantially the entire periphery of each article. I have now mounted these gripping members so that they may be quickly and easily moved to and from operative and inoperative positions and have provided means for yieldingly and continuously urging or holding the members in engagement with the article to prevent its movement lengthwise on the form. To these ends, the gripping or holding members 8 and 9 are carried respectively on the outer ends of levers 12 and 13 pivotally mounted at 14 on a suitable supporting frame 15, which in this instance is removably mounted on the base of the drying form. The levers 12 and 13 in this instance are in the form of bell cranks, the opposite arms 16 and 17 of which are connected by rods 18 and 19 respectively. The arms 16 and 17 are so arranged that when the gripping members are in the operative position shown in full lines in Fig. 2, the rods 18 and 19 will be disposed in a horizontal plane above the pivots 14. The gripping members in this position are urged by a spring pressure 40 against the form to hold an interposed article against movement thereon. This yielding pressure is imposed in this instance by contractile springs 21 connecting the rods 18 and 19. The springs also serve to hold the gripping members in an inoperative position as shown in dotted lines in Fig. 2, in which the arms 12 and 13 after having been swung outwardly, bringing their rods 18 and 19 respectively below the horizontal plane of the pivots 14, will be limited by contact against the stops 22 formed in this instance on the upright portions of the supporting frame 15. In order to move the gripping members to and from their several positions in unison, I have connected them by means of a link 23 which is adapted to be moved vertically by actuation of a rod 24 connected medially to the link. The rod 24 in turn may be operated either by a foot pedal or suitable hand lever to enable quick movement of the gripping members. Or, if desired, a crank may be employed for moving the gripping members to inoperative position. As shown in Fig. 2, a crank 25 fixed to a shaft 26 mounted on the frame

15 is adapted to oscillate an arm 27 also fixed to the shaft 26 and interposed between the rods 18 and 19. Upon movement of the crank in a counterclockwise direction, the levers 12 will be drawn outwardly to an inoperative position, and by swinging the crank in the opposite direction until its arm engages the rod 19, the levers 13 will also be swung to inoperative position. With an actuating device of this kind the rock shaft 26 may be extended to co-operate with a series of gripping devices of the character in mind, and by mounting an arm 27 on the shaft 26 in co-operative relation with each gripping device all of the gripping members on one side of the forms may be withdrawn by one operation of the crank 25 and those on the other side may be simultaneously withdrawn by reverse movement of the crank. It will thus be seen that my invention contemplates the provision of a common operating member adapted for actuating the grippers of a plurality of gripping devices to quicken the work.

When the forms are empty, the gripping members are in the inoperative position shown in dotted lines in Fig. 2. The attendant places a knitted article on the form, draws the article down until a certain gage or mark is reached, whereupon he will swing the gripping arms inwardly to hold the end of the article in the desired position. The result is that the article will not draw upwardly on the form during the drying process, but will be positively held to a given length, thus obviating the necessity of afterwards assorting and mating the articles as is now the common practice. Since the forms are generally arranged in rows, certain series of forms would be connected by a single shaft 26 or an operating member connected with the several members 24 of said series, if operating members of the latter type are used. Thus, when the articles in this series have been dried the attendant will withdraw all the gripping members by quick actuation of the crank or other operating member employed, so that the articles of this series may be removed with the same speed and dispatch and in the same order as though no gripping device had been employed. Thus, a gripping device of this character requires but very little additional time on the part of the operator and insures drying of the articles to uniform or given lengths.

It is believed that the foregoing conveys a clear understanding of my invention and of the objects prefaced above, and while I have illustrated and described but a single practical working embodiment of my improvements with the exception of the operating means of which two forms are shown, it should be understood that various changes might be made in the construction

and arrangement without departing from the spirit and scope of the invention as expressed in the appended claims, in which—

I claim:

5. 1. The combination of a drying form upon which a knitted article is adapted to be drawn, gripping members adapted to hold the article on opposite sides of the form, bell crank levers carrying said gripping members, and spring actuated means arranged so that the spring pressure will hold the bell crank members in operative and inoperative positions.
10. 2. The combination of a hollow form over which a garment to be dried is adapted to be stretched, of a clamp at each side of the form for preventing a garment from creep-

ing thereon, one of said clamps being in the form of a bell-crank lever, means for swinging said lever into and out of garment-clamping position, a connection between the clamps for causing them to move in unison, and a spring for holding the clamps both in and out of said garment-clamping position.

3. The combination with a hollow form 25 over which a garment to be dried is adapted to be stretched, of a clamp at each side of the form for preventing the garment from creeping thereon, means for moving said clamps into and out of a garment clamping position, and spring actuated means for holding the clamps both in and out of said garment-holding position.

GUST O. MORTON.
